UNITED STATES PATENT OFFICE

FRANK B. YINGLING, OF HAMILTON, OHIO, ASSIGNOR TO THE CERAMIC MACHINERY COMPANY, OF HAMILTON, OHIO

HYDRAULIC PUMP

Application filed October 4, 1927. Serial No. 223,899.

My present invention relates to improvements in hydraulic pumps which while adapted for various uses, are especially designed for use in supplying motive power for "pushing" industrial carriers or vehicles, such as railway cars, through the tunnels of kilns for ceramic ware. As thus used in the trade, the pumps or pushers are required to operate continuously throughout the twenty-four hours of the day in order to maintain the desired schedule and capacity of the kiln, and therefore to secure maximum efficiency, the equipment must be rugged and durable, requiring a minimum amount of interruption for repairs, oiling, etc., and indefinite service.

So far as I am aware, no pumps or pushers, are now in use that can attain these desired results at an economical cost, and I have therefore devised the present pump for accomplishing these purposes.

My invention consists in novel combinations and arrangements of parts involving the motive fluid or hydraulic pump of the upper rectilinear type, and its automatic lubricating system, whereby the parts of the machine are compactly arranged and readily accessible for packing, adjustments, repairs, etc.

In the accompanying drawings, I have illustrated one complete example of the physical embodiment of my invention wherein the parts are combined and arranged according to the best mode I have so far devised for the practical application of the principles of my invention.

Figure 1 is a view partly in elevation and partly in vertical section showing a three-cylinder compressor or pump embodying my invention;

Fig. 2 is an enlarged vertical sectional detail view at line 2-2 of Fig. 1 showing a portion of the oil return pipe of the lubricating system;

Fig. 3 is an elevation of the pump as seen from the right end of Fig. 1;

Fig. 4 is a vertical sectional detail view at line 4-4 of Fig. 1 showing one of the compressor or pump units and a portion of the lubricating system;

Fig. 5 is a vertical sectional detail view at line 5-5 of Fig. 1 showing the oil pump of the lubricating system;

Fig. 6 is a sectional view at line 6-6 of Fig. 5; and

Fig. 7 is a vertical sectional view showing the lubricating oil pan and parts of the hydraulic pump.

In carrying out my invention, I have provided a machine somewhat similar in design and appearance to the motor for an automobile, in which the lubrication is automatically provided for, and in which the operating parts are made accessible so that repairs or adjustments may readily be made.

In the installation of the hydraulic pump with the pusher mechanism of a kiln, the suction manifold 1 of the pump is connected by pipe 2 to an oil tank 3 of suitable capacity for maintaining the motive fluid supply for the carriers or cars, and this supply tank may be filled by removing the cap 4. The oil or motive fluid is discharged from the discharge manifold 5 to the discharge pipe 6 leading to the pusher equipment, and the return pipe, not shown, of the motive fluid system is usually connected at 7 in Fig. 3 to complete the circulation of the motive fluid or oil.

The tank 3 in the form of a cylinder is supported by straps 8 beneath the stand 9, which stand has the usual legs, and the base 10 of the hydraulic pump is bolted to the top of the stand. Above the flanged base is arranged and bolted a pump housing or casing 11 having a removable side plate or door 12 to give access to the interior of the casing, and the flanged top of the casing 13, is bolted on the top of the casing to complete the pump enclosure.

The interior of the top is made accessible for repairs, packing, etc., by the removal of a side plate or door 14.

The motive fluid pump is operated preferably by means of an electric motor 15 secured on the stand 9 and with its shaft 15' and driving pinion 16 actuating a train of gears 17, 18, 19, the latter gears on the eccentric shaft 20 which is journaled in bearings 21 of the casing 11. The eccentric shaft extends hori-

zontally above the pump base and as here shown is provided with three eccentrics 22 for operating a complementary number of pump units each including a connecting rod 23, slide head 24 with the wrist pin 25. These 5 slide heads are cylindrical and in the form of pistons, and they reciprocate in the upright cylindrical cross heads 26 which are cast integral with the casing or housing 11, and these cross heads are provided with suitable 10 linings as 27.

To each slide head 23 a pump plunger 28 is secured with the lower threaded reduced 15 end 29 of the plunger screwed into a complementary socket 30 of the slide head.

Above the top 13 of the casing three hollow 20 pump heads 31 are located, each having a bottom boss 32 seated in an opening 33 and secured as by bolts to the top 13. The plungers reciprocate in these heads through packing glands 34 and packing nuts 35 and each head has a chamber 36 communicating by 25 port 37 with the valve chamber 38 in which are located inlet ball valves 39 and outlet 30 valves 40 coacting with their respective valve seats or bushings 41 and 42. The inlet valve 39 admits motive fluid or oil from the suction manifold 1 through port 43, and outlet or discharge valve 40 permits oil under pressure to be forced through passage 44 to the discharge 35 manifold 5. Thus the three pumping units are arranged and timed to successively draw motive fluid from the intake manifold of the compressor or pump chambers 36 and successively force these charges of motive fluid to the discharge manifold, and pipe 6 in a substantially continuous and uniform stream to insure a regular and uniform pressure of motive fluid for the purpose of propelling or 40 pushing the kiln cars or other vehicles. The motive fluid is continuously circulated and is of course replenished from time to time as required.

The suction and discharge manifolds communicate with all of the pump heads and extend transversely of the heads with bosses 45 seated in sockets in the sides of the heads and attaching bolts 46 are employed to clamp the manifolds to the heads. The vertical chambers 38 of the heads are bored with open ends 50 and these ends are closed by removable screw plugs 46' to provide facile means of gaining access to the pump heads when necessary.

The operating parts of the several pump units are lubricated automatically by an oil pump which operates synchronously with the pumping mechanism. This lubricating oil pump is actuated through the use of a cam or eccentric groove 47 in one face of the gear 19, and this gear as seen in Fig. 6 revolves in the sump 48, for oil, formed in the bottom of the engine base. A pump plunger 49 is designed to reciprocate in the barrel or bore 50, and a cross head or pin 51 on this plunger has its end extending into the eccentric groove 47

of the gear 19. Thus as the gear revolves the lubricating pump is reciprocated in the barrel 50 to pump the oil. In Fig. 5, the lubricating pump is best shown and is provided with an intake ball valve 52 and an outlet ball valve 53, springs 54 being employed as usual in connection with these ball valves. The ball valve 52 controls the intake port 55 and the ball valve 53 controls the outlet valve 56 in usual manner, and the oil chamber 57 communicates with the ports and with the barrel of the pump as shown. The oil is lifted past the outlet valve 53 into the pipe 58 and the upper end of this pipe opens into a longitudinal groove 58' from which extend a series of lubricating grooves 59. Each one of these grooves 59 extends to a cross head cylinder for the purpose of lubricating the slide head.

In the housing 13 is enclosed an oil pan 60 to catch any motive fluid or oil as it drips or drops from the packed joints of the pump plungers, and the return pipe 61 from this pan conveys the motive fluid or oil back to the bottom of the engine base and through a sleeve 62 that is formed integral with one of the bearings 21. A pipe connection 63 is made between the pipe 61 and the casting 62, and a sleeve 64 is cast integral with the bottom of the engine base. This vertically arranged sleeve casting 64 opens below the pump base and a pipe 65 is screwed into the lower end of the casting from beneath the stand and another pipe section 66 extends to the tank 3 as indicated in Figs. 1 and 2.

The pump plungers are each provided with a conical shield 67, and the oil pan is provided with annular flanges 68 encircling the pump plungers, to prevent the motive fluid or operating oil that may leak through the packed joints from running down the plungers. The flanges 68 do not in practice fit tight around the plungers but they are of sufficient height to prevent any motive fluid from the pan having access to the plungers, and the conical shields shed the motive fluid to the pan.

Various changes and alterations may be made in the structure as exemplified in the drawings, as for instance the number of pump units may be varied, and other changes are contemplated. The parts as thus assembled form a hydraulic pump in which the operating parts are continuously lubricated by the operation of the pump itself, and the parts of the base, intermediate housing, and top casing are so assembled and arranged, that the access may readily be had to any of the operating parts requiring attention for repairs or adjustments.

Having thus fully described my invention, what I claim as new and desire to secure by Letters Patent is—

1. The combination with a base, an intermediate housing having a plurality of tubular cross head guides cast integral therewith,

a plurality of reciprocating plungers, and cylindrical cross heads on said plungers for co-operation with the cross head guides, a top casing, a pump head mounted on the casing and having chambers for the plungers, a suction manifold and a discharge manifold mounted on the head, check valves for controlling communication between said chambers and the manifolds, and driving means for the pump.

10 2. The combination with a base and a shaft journaled therein, driving means for the shaft and a plurality of eccentrics on the shaft, of an intermediate housing having cylindrical cross head guides integral therewith, a top casing, a plurality of pump plungers and transmission mechanism between said plungers and the eccentrics, a pump head mounted on the casing and having chambers for the plungers, a suction manifold and a discharge manifold mounted on the head, means for controlling communication between said chambers and the manifolds, and means for rotating said shaft.

15 3. In a motive fluid pump the combination with a base adapted to form an oil reservoir, an intermediate housing and a top casing, of a plurality of reciprocating plungers within said housing, means for operating the plungers, an internal lubricating system, means for driving the pump, means for actuating the lubricating system from said driving means, a pump head mounted on the casing having chambers for the plungers, a suction manifold and a discharge manifold mounted on the casing head, and means for controlling communication between said chambers and the manifolds.
